UNITED STATES PATENT OFFICE.

SIDNEY BENEDICT KAHNWEILER, OF ATLANTIC CITY, NEW JERSEY.

DESIGN FOR TWEEZERS.

60,455.

Specification for Design. Patented Feb. 21, 1922.

Application filed August 30, 1921. Serial No. 497,062. Term of patent 14 years.

To all whom it may concern:

Be it known that I, SIDNEY B. KAHNWEILER, a citizen of the United States, and a resident of Atlantic City, in the county of Atlantic and State of New Jersey, have invented a new, original, and ornamental Design for Tweezers, of which the following is a specification.

Reference is to be had to the accompanying drawing, in which—

The figure is a perspective view of tweezers showing my new design.

I claim:

The new and ornamental design for tweezers as shown.

SIDNEY BENEDICT KAHNWEILER.
